[57] CLAIM

The ornamental design of a humorous megaphone, substantially as shown and described.

DESCRIPTION

FIG. 1 is a side view of a megaphone showing our new design, the opposite side being a mirror image thereof;
FIG. 2 is a front view thereof;
FIG. 3 is a rear view thereof;
FIG. 4 is a top view thereof;
FIG. 5 is a bottom view thereof;
FIG. 6 is a perspective view thereof; and,
FIG. 7 is another perspective view of our humorous megaphone with the tongue fully extended therefrom.
